(57) **CLAIM**

The ornamental design for a metatarsal guard, as shown and described.

DESCRIPTION

The present application is filed along with United States Design Patent Application Nos. 29/667,244 and 29/667,246, the disclosures of which are incorporated herein by reference.

FIG. 1 is a perspective view of a metatarsal guard according to a first embodiment of the design;

FIG. 2 is a top view of a metatarsal guard of the embodiment of FIG. 1;

FIG. 3 is a bottom view of a metatarsal guard of the embodiment of FIG. 1;

FIG. 4 is a right view of a metatarsal guard of the embodiment of FIG. 1;

FIG. 5 is a left view of a metatarsal guard of the embodiment of FIG. 1;

FIG. 6 is a front view of a metatarsal guard of the embodiment of FIG. 1;

FIG. 7 is a rear view of a metatarsal guard of the embodiment of FIG. 1;

FIG. 8 is a perspective view of a metatarsal guard according to a second embodiment of the design;

FIG. 9 is a top view of a metatarsal guard of the embodiment of FIG. 8;

FIG. 10 is a bottom view of a metatarsal guard of the embodiment of FIG. 8;

FIG. 11 is a right view of a metatarsal guard of the embodiment of FIG. 8;

FIG. 12 is a left view of a metatarsal guard of the embodiment of FIG. 8;

FIG. 13 is a front view of a metatarsal guard of the embodiment of FIG. 8;

FIG. 14 is a rear view of a metatarsal guard of the embodiment of FIG. 8;

FIG. 15 is a perspective view of a metatarsal guard according to a third embodiment of the design;

(Continued)

FIG. 16 is a top view of a metatarsal guard of the embodiment of FIG. 15;
 FIG. 17 is a bottom view of a metatarsal guard of the embodiment of FIG. 15;
 FIG. 18 is a right view of a metatarsal guard of the embodiment of FIG. 15;
 FIG. 19 is a left view of a metatarsal guard of the embodiment of FIG. 15;
 FIG. 20 is a front view of a metatarsal guard of the embodiment of FIG. 15; and,
 FIG. 21 is a rear view of a metatarsal guard of the embodiment of FIG. 15.
 The broken lines depict portions of the metatarsal guard that form no part of the claimed design.
